DESIGN FOR A TOY ANIMAL FIGURE

Morris C. Levich, New York, N. Y.

Application May 1, 1948, Serial No. 146,127

Term of patent 14 years

(Cl. D34—2)

To all whom it may concern:

Be it known that I, Morris C. Levich, a citizen of the United States, residing in the Borough of Manhattan, city, county, and State of New York, have invented a new, original, and ornamental Design for a Toy Animal Figure, of which the following is a specification, reference being had to the accompanying drawing, forming part thereof.

On the drawing,

Fig. 1 is a side elevational view of a toy animal figure, embodying my new design;

Fig. 2 is a front elevational view of the toy animal figure, shown in Fig. 1; and

Fig. 3 is a plan view of the toy animal figure, shown in Fig. 1.

I claim:

The ornamental design for a toy animal figure, substantially as shown.

MORRIS C. LEVICH.
